UNITED STATES PATENT OFFICE.

LYDIA RAESSER, OF MILWAUKEE, WISCONSIN.

DESIGN FOR A SERVER.

46,845.

Specification for Design.

Patented Jan. 5, 1915.

Application filed September 9, 1914. Serial No. 860,949. Term of patent 14 years.

To all whom it may concern:

Be it known that I, LYDIA RAESSER, a citizen of the United States, residing at Milwaukee, in the county of Milwaukee and State of Wisconsin, have invented a new, original, and ornamental Design for Servers, of which the following is a specification, reference being had to the drawing forming a part of my application filed September 9, 1914, Serial No. 860,949.

Figure 1 is a perspective view looking at the top of the server, illustrating my new

design; Fig. 2 is a perspective view looking at the bottom thereof; and Fig. 3 is a vertical sectional view taken through the article, illustrating my design.

I claim:

The ornamental design for a server, as shown.

LYDIA RAESSER.
